(57) **CLAIM**

The ornamental design for a coffee filter bag, as shown and described.

DESCRIPTION

FIG. 1 is a perspective view of a coffee filter bag showing my new design;

FIG. 2 is a side view thereof;

FIG. 3 is another side view thereof;

FIG. 4 is a right-side view thereof;

FIG. 5 is a left side view thereof;

FIG. 6 is a top view thereof; and,

FIG. 7 is a bottom view thereof.

The broken lines in the drawings depict portions of the coffee filter bag that form no part of the claimed design.
